[57] CLAIM

The ornamental design for a paint shield for an electrical fixture, as shown and described.

DESCRIPTION

FIG. 1 is a front elevational view of a first embodiment of a paint shield for an electrical fixture showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a right side elevational view of the first embodiment thereof, shown partly in cross-section;

FIG. 8 is a right side elevational view of the first embodiment thereof, shown partly in cross-section; and,

FIG. 9 is a perspective view thereof.

The broken line portions of FIGS. 7 and 8 are for illustrative purposes only and form no part of the claimed design.

FIG. 1

FIG. 2

FIG. 3

FIG. 4

FIG. 5

FIG. 6

FIG. 7

FIG. 8

FIG. 9
